(57) **CLAIM**

The ornamental design for a storage divider, as shown and described.

DESCRIPTION

FIG. 1 is a front top left perspective view of the storage divider, showing my new design, with the front top right perspective view being a mirror image thereof;

FIG. 2 is a front bottom left perspective view thereof;
FIG. 3 is a left side elevation view thereof, with the right side elevation view being an identical image thereof;

FIG. 4 is a front elevation view thereof, with the rear elevation view being an identical image thereof;

FIG. 5 is a top plan view thereof; and,

FIG. 6 is a bottom plan view thereof.

The broken lines shown in the drawings depict portions of the storage divider that form no part of the claimed design.
